(57) **CLAIM**

The ornamental design for a pneumatic tire, as shown and described.

DESCRIPTION

FIG. 1 is a front elevational view of the pneumatic tire showing my new design, it being understood that the tire pattern repeats circumferentially throughout the outer circumference;

FIG. 2 is a perspective view of one side of the pneumatic tire shown in FIG. 1; and,

FIG. 3 is a side elevational view of one side of the pneumatic tire shown in FIG. 1, the opposite side being of identical appearance.

In the drawings, the broken lines show the inner bead and sidewall of a pneumatic tire and form no part of the claimed design.

1 Claim, 3 Drawing Sheets

FIG. 1

FIG. 2
